UNITED STATES PATENT OFFICE.

WILLIAM N. KIDDER, OF PROVIDENCE, RHODE ISLAND.

SEPARABLE BUTTON OR STUD.

No. 808,988.

Specification of Letters Patent.

Patented Jan. 2, 1906.

Application filed March 29, 1905. Serial No. 252,745.

To all whom it may concern.

Be it known that I, WILLIAM N. KIDDER, a citizen of the United States of America, and a resident of Providence, in the county of Providence and State of Rhode Island, have invented certain new and useful Improvements in Separable Buttons or Studs, of which the following is a specification.

My invention has relation to improvements in link or cuff buttons and studs of the separable type—that is, of a type wherein the buttons or studs are detachable one from the other.

In the accompanying sheet of drawings, Figure 1 is a side elevation of a separable button embodying my improvement. Fig. 2 is a partial side elevation and partial sectional view of a separable button embodying my improvement, showing the supplemental or auxiliary presser member. Fig. 3 is a cross-sectional view, enlarged, taken on line $x-x$ of Fig. 1 and Fig. 4 is a similar sectional view taken on line $o-o$ of Fig. 2. Fig. 5 is an enlarged transverse sectional view taken on the line 5 5 of Fig. 2.

In my improved separable button or stud A the front head member a has a tubular shank a' , having an oval or flattened form transversely rigidly secured to its back. The rear end of said shank or post a' is open to freely receive the yielding stem c about to be described. At or near said open end the shank is cut away transversely on its upper side or edge to form the opening or notch a^2 .

The rear head member b of the button is detachably secured to the shank of the front a by means of the elongated U-shaped yielding stem c . The rear end c' of the lower arm of the stem is soldered or otherwise rigidly secured to the member b , the other or free arm c^2 of the stem having a push lug or projection c^3 on its upper side or edge adapted to automatically spring into said notch a^2 of the shank when the parts are in the normal position or relation, as clearly shown in Fig. 2. It will be seen that the stem c forms a guide and support for the head b by bearing snugly against the upper and lower interior surfaces longitudinally of the shank, thereby maintaining the back head in position and at the same time giving it increased stability and

also preventing it from turning axially. The tubular shank a' projects from a boss a^x on the inner face of the button - head a , and the free end of this tubular shank abuts 55 against a smaller boss a^y on the inner face of the button - head b , the bore through the boss a^y registering with and being substantially of the same size as the bore in the tubular shank a' . The button may be readily 60 separated by simply pressing downwardly upon the lug c^3 until it is flush with the adjacent interior surface of the hollow shank, at which instant the parts are in position to be drawn away from each other in an end- 65 wise direction.

In some cases it may be desirable to provide the free end c^2 of the stem with a vertically-bent extension or link n , the upper end of the latter projecting through a hole formed 70 in the rim of the rear head b , as clearly indicated in Fig. 2. In this case the members a and b may be separated or unlocked from each other by pressing downwardly upon the exposed end of the said extension n , thereby 75 depressing the said lug c^3 until it is flush with the shank's interior surface, substantially as before stated.

I claim as my invention—

1. A separable button comprising two button-heads one of which is hollow, and a curved hollow one-piece shank attached to one head and adapted to bear against the other head, said shank being formed with a notch near one end, a spring composed of two curved 85 integral arms, one of said arms being attached to the inner wall of the outer plate of the hollow head, the other of said arms carrying a lug adapted to seat in the notch of the shank, said last-named arm extending into 90 the hollow head, and a link arranged in the hollow head and engaging said last-named arm and extending through an opening in the perimeter of the hollow head.

2. A separable button comprising two 95 heads, one of which is hollow, and a hollow shank carried by one head and bearing against the other head, said shank being formed with a notch near one end, a spring composed of two integral arms, the ends of 100 both said arms being located in said hollow head and the end of one of said arms being

attached within the hollow head while the other end is free, said free end carrying a lug adapted to seat in the notch in the shank, and a link arranged in the hollow head, and engaging said free end, and extending through an opening in the perimeter of the hollow head.

Signed at Providence, Rhode Island, this 27th day of March, 1905.

WILLIAM N. KIDDER.
